HANDBAG FASTENER

David Damast, 22-14 40th Ave.,
Long Island City, N.Y. 11101

Filed Feb. 16, 1967, Ser. No. 5,699

Term of patent 3½ years

(Cl. D87—2)

Fig. 1.

Fig. 3.

Fig. 4.

FIG. 1 is a perspective view of a handbag fastener showing my new design,

FIG. 2 is a top plan view thereof,

FIG. 3 is a front elevational view thereof, and

FIG. 4 is a side elevational view thereof, and

FIG. 5 is an enlarged perspective view with the knob turned on its support to effect locking action.

The rear of the handbag fastener is flat and smooth without ornamentation.

I claim:

The ornamental design for a handbag fastener, substantially as shown, and described.
